DIE MECHANISM AND METHOD

Earl M. Amesbury, Chicago, Ill., James G. Macormack, New York, N. Y., Seward M. Roberts, Chicago, Ill., and Fleck W. Sample, Forest Hills, N. Y., assignors to American Flange & Manufacturing Co., Inc., New York, N. Y., a corporation of Illinois

Application June 28, 1939, Serial No. 281,506

15 Claims. (Cl. 153—1)

This invention relates to mechanism and methods for securing closure bushings in place in openings in sheet metal container walls. Drums, barrels and pails intended for the transportation, storage and dispensing of liquids, such as oils, gasoline and chemicals are the types of containers with which the invention is most commonly concerned. The walls of such containers are formed of relatively thin sheet metal and have mounted therein screw-threaded flanges or bushings formed for the effective, leak-proof reception of closure plugs. Commonly two openings of different sizes are provided in the containers under consideration, one for filling and the other for discharging; and each is formed to not only receive a leak-proof closure plug to assure safe transit of the contents, but to receive a faucet, pump or like dispensing means in place of one or the other of such closure plugs when the container has reached its destination. The flanges or bushings of the type contemplated herein are usually secured in the container wall by pressing or forming operations and the construction and manner of mounting of said flanges or bushings is such that they remain in leak-proof engagement in the container wall opening throughout the life of the container.

Heretofore it has generally been the practice to perform two distinct operations to complete such securing, the first of which concerns the perforation of the container wall and formation of whatever embossing, or the like, is desired around the opening and the second of which concerns the introduction of the flange or bushing into the opening and the securing of the same in place therein. In order to perform these operations on an economic commercial scale on either the head or wall of a container, the practice heretofore generally followed required the use of twice as many presses and twice as many sets of dies as there were openings to be equipped with flanges or bushings. At least one workman was needed to operate each press with a helper or two for the group of presses in order to remove the finished products and keep the operators supplied with sheets and flanges. Of course, the container walls can be stored up after the first operation has been performed and the dies changed, so that the same press may be used for the second operation. Such changing of dies, however, takes considerable time and this practice is not economical in a plant of any size. Furthermore, containers of the types under consideration are only made up on order and are usually not ordered until they are needed in a hurry.

With this prior scheme of operation, the chances of failure and consequent interruption of the process of manufacture are multiplied by the number of die sets and number of presses employed. The probability of such interruption occurring is seen to be very likely from a consideration of the refinements of the die parts employed, the continuous operation of the presses and the fact that the labor employed is unskilled and often careless of such features as the proper lubrication and exact setting of the dies and die parts. It is also to be borne in mind that breakage of die parts is costly. This cost is generally not borne by the user of the dies, unless indirectly, since such dies and die parts are, in most instances, loaned and replaced by the manufacturer of the flanges or bushings.

Recently there have been several isolated suggestions on mechanisms for performing both of the above discussed operations in one. Under special circumstances, such as when the flange or bushing employed had quite a small diameter, one of the suggested mechanisms performed more creditably than would have been expected from an examination of it. However, each one had its limitations and the limitations were such that the mechanisms could not be relied upon for general application of all sizes of bushings under all conditions. The construction of the instant invention, on the contrary, is completely reliable for all sizes and conditions of work and can be operated continuously to insert flanges or bushings in sheet metal walls by performing the perforating and embossing and the inserting steps all in one operation in a single stroke of the press. This is due to the fact that the instant invention takes into consideration all the factors which would tend to impair the operativeness of the mechanism and includes steps in its method and features in its mechanism which wholly eliminate all possibilities of failure. Accordingly, the method and mechanisms of the instant invention provide the first commercially sound, universally adaptable solution of the problem of inserting flanges or bushings in sheet metal walls in one operation.

A principal object of the invention is to provide a mechanism which can be operated continuously for the insertion of flanges or bushings of any desired size in sheet metal walls in one operation.

Another principal object of the invention is the provision of a method or process by which such insertion of bushings can be carried out.

55 Another object is to provide a method of per-

formance, whose steps are so chosen, and a mechanism, whose parts are so constructed and related, that in the insertion of a flange or bushing in one operation the chances of wear and breakage of parts are reduced to a minimum and continuous operation is assured.

A further object of the invention is the provision of a die mechanism for inserting flanges or bushings in sheet metal walls in one operation, in which mechanism, provision is made, during all stages of operation, for the proper relation of the flange and wall to each other and to the parts of the die mechanism.

A more specific object is the provision in a single stroke operation for the insertion of flanges or bushings in sheet metal walls, of support for the flange or bushing to prevent it from being distorted during the first stages of the operation to such an extent that it will jam the die mechanism, injure certain of the most vital parts thereof or be precluded from being properly secured in place in the sheet metal wall.

Other objects of the invention will be apparent to those skilled in the art to which the invention relates and will also appear from the following description taken in connection with the accompanying drawings wherein:

Figure 1 is a vertical section of so much of one form of mechanism as is necessary to illustrate the invention showing such mechanism in neutral position with a sheet metal wall and flange positioned ready for the commencement of the securing operation;

Fig. 2 is a fragmentary section similar to Fig. 1 showing the position of the parts just after the first or sheet perforating stage of the operation has been completed;

Fig. 3 is a similar view showing the position of the parts after completion of the next stage in the operation in which the sheet metal wall has been drawn over the flange;

Fig. 4 is a similar view showing the position of the parts at the commencement of the curling or forming of the closure flange neck over the container wall neck;

Fig. 5 is a similar view, but taking in more of the mechanism, in which the securing of the flange or bushing to the sheet metal wall is in its last or completed stage with the embossing of an octagon in the sheet metal wall to embrace the octagon of the flange completed;

Fig. 6 is a plan view looking at the upper die mechanism of Fig. 1 from underneath or as from line 6-6 of Fig. 1;

Fig. 7 is a plan view of the lower die mechanism looking down thereon as from line 7-7 of Fig. 1;

Fig. 8 is an enlarged cross-sectional view of the sheet metal wall and flange secured together;

Fig. 9 is a detailed perspective view in section showing the manner in which the cams are mounted in the lower compression ring;

Fig. 10 is a perspective view of one of the cams itself;

Fig. 11 is a perspective view partly in section of the cam-follower-ring of Figs. 1 to 7;

Fig. 12 is an enlarged perspective view of the cam of Figs. 1 to 7;

Fig. 13 is a perspective of the shim shown in place in Fig. 9;

Fig. 14 is a view similar to Fig. 1, but showing a modified construction and;

Fig. 15 is a view of the modification showing the mechanism thereof in final position with the air cushion in part elevation and part section.

The sheet metal wall of the container, or the like, to which the flange or bushing is to be applied is shown generally at 1 and is perforated to form an opening, whose initial appearance is as shown at 2 in Fig. 2. The wall surrounding that opening is drawn into a neck shown in its final state at 3 in Fig. 8; while at the base of the neck there is formed an embossing 4 of octagonal or other irregular contour. A flange or bushing, generally indicated at 5, has a neck 6 received within the neck 3 and a laterally extending flange 7 which is not only received non-rotatably within the embossing 4, but, in the system under consideration, acts as the male die in the formation of the embossing 4. The upper end of the neck 6 is shown at 8 as curled or formed over against the end of neck 3, which curling or forming is shown in its initial stage in Fig. 4 and in its completed stage in Figs. 5 and 8. A gasket 9 is received within the annular pocket formed by the flaring surface at the lower end of neck 3 and the opposed annular walls of the bushing 5 and its flange 7. This gasket is drawn into tight leak-proof engagement by the final curling or rolling of portion 8 and forming of the embossing 4 as shown in Fig. 5, wherein the bushing is not only secured in position in the wall, but is drawn up tightly into the receiving pocket provided for it. Where the portion 8 extends above the screw-threaded portion of neck 6, it is reduced in thickness from its inner side as best shown in Figs. 1 and 3. This reduction facilitates the forming or curling of portion 8 and eliminates cracking or scaling of this portion which might otherwise occur. While this particular relation between the wall and the bushing or flange is pointed out in detail, the same is done in an introductory sense and in order to render the function and operation of the die mechanism more readily understandable, but it is to be understood that the principles on which the invention is based are not limited to the specific relation of parts shown or to the securing of the particular bushing shown in the opening in the wall as shown.

The die mechanism of the invention is adapted for reception in a standard press so illustration of such press is not deemed necessary. This die mechanism consists of upper and lower parts which operate from opposite sides of the sheet to which the bushing is to be secured. The lower part is, as a unit, stationary though it contains movable elements. The upper die part is movable with the slide portion or ram 10 of the press and it is through the movement of this part, as well as through the movement which its elements impart to the elements of the lower die member, that the perforating, drawing and forming takes place.

The main portion or shoe of the upper die part is generally shown at 11 and has a shank 12 which is received in a recess such as 13 in the ram 10 being secured in place therein by a clamping plate, or like device. This particular securing and the use of a clamping plate are conventional, form no particular part of the invention, and, of course, may be varied in accordance with the facilities afforded by the press which is employed.

A pressure ring 15 is mounted below the lower face 14 of the upper die shoe 11 for relative movement with respect thereto. This pressure ring is guided and limited in its downward movement by bolts 16 whose cylindrical heads have a limited sliding movement in bores 17 formed downwardly from the upper surface of die shoe 11. These

bolts are threaded into the pressure ring and are locked in place therein by means of set screws 18 extending inwardly from the periphery of the pressure ring. In order to control the relative movement between the pressure ring 15 and the die shoe 11 and to determine the force to be transmitted thereby, a series of compression springs 19 are provided having their upper portions received within bores 20 which extend upwardly from the lower face 14 of the upper die shoe 11. The lower portions of springs 19 are similarly received within bores 21 which extend a short distance downwardly from the upper face of pressure ring 15. The number and size of springs 19 is determined by the force which it is desired to transmit. They may be centered on a circle whose center is on the axis of the die shoe or be placed in staggered relation in separate concentric circles as shown in Fig. 6. Likewise the bolts 16 may be of any required number, though for the purposes of illustration four are shown as is seen from Fig. 6.

Extending into die shoe 11 from the lower face 14 thereof, is a shallow circular depression 22 whose center is on the center line of the die shoe 11. This depression 22 snugly receives the upper end of a rolling anvil 23 which is generally cylindrical in shape and has an outer cylindrical sliding bearing surface 24. The lower end of this anvil is provided with an annular rolling or forming surface 25 generally arc shaped in cross-section, but whose inner wall departs from the arc into an inclined pickup portion 26 leading from the arc to a position in advance of it. A stepped bore generally shown at 27 extending inwardly from the lower face of the rolling anvil has an enlarged entrant portion 28 and a restricted upper portion 29 between which there is formed an abutting shoulder 30. Another and vitally important feature of the rolling anvil 23 is the annular leading ring 31 which is formed on the lower end thereof between the entrant portion 28 of bore 27 and the pickup portion 26. As shown, ring 31 is slightly in advance of the open mouth of rolling surface 25 for purposes which will appear hereinafter.

A perforating punch 32 having an upper portion stepped to co-mate with the stepped bore 27 in which it is received has a lower portion, on its larger diameter, extending downwardly considerably in advance of the lower end of the rolling anvil. This perforating punch has a cutting edge 33 which is the furthest advanced of any of the elements of the upper die member. This cutting edge is shown as fluted at 34 for facilitating the perforating operation, but may be plain or of any other contour desired for effective operation. The perforating punch 32 is centrally bored to receive a securing bolt 35 whose head 36 is counter-sunk into the free face of the punch and whose upper end is screw-threaded into a receiving bore 37 in the upper die shoe 11. As is obvious from the showing in the drawings, bolt 35 not only holds the perforating punch 32 in place, but also due to abutting shoulder 30 and depression 22 locks the rolling anvil 23 in secure and exact position.

Mounted for vertical sliding movement on the sliding surface 24 of anvil 23 is an upper embossing ring 38. This ring, which is generally annular in formation, has a flat upper surface 39 and at the inner edge of that surface an upwardly extending mounting collar 40. This collar has a sliding surface 41 for sliding engagement with the surface 24 of rolling anvil 23, and

an outer abutting surface 42. The ring 38 is secured to, in engagement with, and operates with, the pressure ring 15. This cooperation is provided by the pressure ring 15 having its lower and inner portion received against surfaces 39 and 42 of the embossing ring 38 and by bolts 43 (Fig. 2), whose heads are counter-sunk into the upper surface of ring 15 and whose shanks extend through the remainder of ring 15 into screw-threaded engagement with embossing ring 38. The embossing ring 38 is formed on its leading face with a clamping surface 44 which is the first portion of this ring to engage the sheet metal wall. This face is recessed at 45 to a depth substantially equivalent to the thickness of flange 7 of bushing 6 and the recess has a contour complementary with respect to flange 7 in order to form the sheet metal wall 1 thereover. The horizontal face of this recess may be provided with upstanding letters or numerals, in order to impress indicia into the drum stock where the same overlies the flange 7. Recess 45 terminates at a circular bore 46 which is provided with a drawing edge 47 for a purpose which will appear hereinafter. Bore 46 extends inwardly a short distance and terminates at stepped shoulder 48 which forms the end of sliding surface 41.

The lower die part (Figs. 1 and 7) is clamped in conventional manner to the bolster plate 50 of the press by means of holdown bolts 51 and clamping plates 52. The bolster plate has an aperture 53 therethrough for purposes which will appear hereinafter. Adjustment of the position of the lower die shoe 54 is provided for by the channels 55 at its ends which are bridged by the plates 52 and through which bolts 51 pass. These ends are in the nature of a flat plate having an upper surface 56 which extends outwardly from an upstanding annular ring 57. Ring 57 has an outer cylindrical wall or shoulder 58 and an inner cylindrical wall 59 which extends downwardly to a bottom surface 60 forming therewith a cam-follower-ring receiving chamber.

A housing, generally indicated at 61 (Figs. 1 and 11) is formed to accommodate various elements of the mechanism, but for convenience it is referred to as the cam-follower-ring. This ring is received within the chamber just described. The outer annular surface 62 of said ring fits closely within surface 59 and its bottom surface 63 seats on the bottom surface 60 of the receiving chamber. The ring is held in place in its receiving chamber by means of bolts 64 whose heads are counter-sunk into the bottom of the die shoe 54 and whose shanks are screw-threadedly received at 65 in the ring. In order not to confuse the drawings only one of these bolts is shown, though normally several would be employed.

The cam-follower-ring 61 is open through its center, as the name indicates, the opening being of various diameters at different positions in its extent. The smallest of these diameters is provided by bore 66 whose purpose is to allow passage of the slugs removed from the sheet by the perforating punch 32. At the upper end of bore 66 the diameter of the opening is increased and a shoulder 67 extends outwardly from the end of the bore to the next cylindrical wall which is indicated by 68. The wall 68, however, is not continuous for at three evenly spaced positions in the circumference thereof there are formed substantially rectangular radially extending channels generally shown at 69. Each of these

channels has vertical side walls 70 extending to the top of the ring and a bottom 71 which is a continuation of the shoulder 61. These channels extend through to the outside 62 of the ring. Bores 72 extend downwardly from each surface 71 and in fact are continued right on through the adjacent portion of die shoe 54, as shown in Fig. 1. The purpose of these bores will appear hereinafter.

Mounted in a slidable fit within each channel 69 is a locking latch generally shown at 73 (Fig. 12). This latch also functions as a cam-follower in which manner movement is imparted to it. These latches are generally rectangular in shape, have their inner faces curved at 74 on the same radius as the surface 68 previously described and are provided on their outer faces with spring centering pins 75. Elongated bores 76 are provided in the latches in such a position as to register with the bores 72 previously described. Bores 76 provide a follower surface 77 at their inner ends designed to be engaged by a cam hereinafter described. In order to urge the latches inwardly, springs 78 (Figs. 1 to 5) are provided acting against the rear surface 79 of the latch 73 and being maintained in proper relation with respect thereto by means of the pins 75. The opposite ends of these springs, which extend beyond the periphery 62 of the cam-follower-ring, are received within bores 80 provided in the adjacent portion of the ring 57 of the die shoe; while set screws 81 carrying locating pins 82 are threadedly received in the outer ends of bores 80 to retain the springs 78 in place and enable the tension on them to be controlled.

Each segment of the wall 68 (Fig. 11), is arcuately recessed at 83 in line with the small bore 84 which extends through from the surface 67 of the follower-ring to the bottom surface of the die shoe where such die shoe partially overlies the aperture 53 in the bolster plate (Figs. 1 and 5). The purpose of bores 84 will appear hereinafter. At the upper end of surface 68 the cam-follower-ring is inset forming a shoulder 85 which extends inwardly to its termination in a vertical annular wall 86, which latter extends upwardly to the top surface 87 of the cam-follower-ring.

Carried on the seat provided by surfaces 85 and 86 is the laterally extending mounting collar 88 of a seating ring or anvil 89 whose top surface 90 is designed to carry the flange or bushing to be inserted (Figs. 1 to 5). The seating ring 89 is held in place against seat 85-86 by means of a bolt 91 whose head is counter-sunk into and whose shank extends up through the cam-follower-ring 61 through a threaded bore which emerges through surface 85 as shown at 92 (Figs. 1 and 11). The inner cylindrical surface 93 of the seating ring 89 has an annular setback 94 at its bottom end.

Mounted for slidable movement within the seating ring 89 is the flanging punch 95. The primary functions of this punch are to cooperate with the perforating punch 32 in the perforating of the sheet and with the embossing ring 38, particularly surface 47 thereof, to draw a neck in the sheet. The flanging punch has a laterally extending collar 96 at the bottom end thereof which is normally received within the setback 94 of anvil 89. However, the body of flanging punch 95 is slidably mounted with respect to surface 93 of anvil 89 and accordingly shoulder 96 is designed to slide out of setback 94 down alongside of surface 68 and vice versa. Shoulder 96 will also slide against the curved faces 74 of the

latches 73 when such latches are drawn back to cause surface 74 to form a continuation of surface 68.

The additional and important function performed by the flanging punch in the present construction is that of a support preventing too great inward collapse of the reduced end 8 of the flange or bushing 5 mounted thereover. To do this the flanging punch 95 normally extends upwardly through the reduced portion 8 and the very upper end of the punch is slightly above the upper edge of the portion 8. Thus, the upper end of the flanging punch is sized and positioned so as to limit the extent to which the reduced portion of flange or bushing 5 may be collapsed by the drawing of the perforated sheet thereover. This limiting position is such that the pickup portion 26 of the curling anvil 23 is readily able to take the end of reduced portion 8 from the upper end of the flanging punch even though the same be collapsed thereagainst. In order, however, for the curling surface 25 to come into engagement with portion 8, provision must be made for retraction of the flanging punch. This provision is made by the structure now to be described.

The lower compression ring shown in detail in Fig. 9 is generally indicated at 99. It has an upper surface 100 designed to cooperate with the surface 44 of the upper compression ring in order to yieldingly clamp the sheet while the perforating, drawing and rolling or curling actions are being carried out. The surfaces 44 and 100 may also be provided with co-mating raised and depressed letters or numerals in order to emboss indicia into the sheet just outside of the perimeter of the flange 7 if such be desired. These indicia may be used in addition to those impressed by the upper surface of recess 45 or they may be used as alternatives thereto.

The ring 99 also has an inner surface 101 shaped to conform to the periphery of the flange 7 of the bushing 5. Below the surface 101, ring 99 provides an inwardly extending lip 102 which is designed to slidably engage the outer surface 45 of the seating ring or anvil 89. Compression ring 99 is precluded from rotating, as will appear hereinafter, operates to prevent rotation of the flange or bushing and therefore assure its proper relation with respect to the surface 45 of the embossing ring 38. In order to control the sliding action of ring 99 a series of springs 103 are provided (Figs. 1 to 5) for operation between the ring and the cam-follower-ring 61. These springs have their upper ends received in bores 104 formed in the underside of the compression ring and their lower ends received in bores 105 extending downwardly from the top surface 87 of ring 61. Springs 103 are decidedly weaker than springs 19 because ring 99 is intended to yield readily under the force exerted by ring 38. Suitable guide bolts are provided for preventing compression ring 99 from sliding upwardly off the outer surface of seating ring 89 and preventing rotation of it, but the same are omitted from the present showing in order to prevent confusion. The bores for receiving such bolts, however, are shown at 104a in Fig. 9 and 105a in Fig. 11.

Another important function performed by the lower compression ring in the instant construction is that of acting as a carrier for the cams which actuate the locking latches 73. These cams, shown in detail in Figs. 9 and 10, have a body portion 106, a mounting portion 107 which

is received within a bore 108 extending through the compression ring 99 and a laterally extending portion 109, which at its upper end provides a shoulder 110 which abuts against either the undersurface 111 of the lower compression ring or against a shim 112a (Figs. 9 and 13) inserted between surfaces 110 and 111 when the same is necessary. This laterally extending portion 109 also provides the means to secure the cam in place in aperture 108 since it is bored downwardly from surface 110 as shown at 112 and receives a counter-sunk securing bolt which extends through from the upper surface of ring 99 as shown at 113. Thus, a rigid mounting and certain securing is provided while still allowing for the introduction of means such as shims 112a for making slight adjustments in the cam action should such adjustments be needed. On the bottom end of the cam body 106 a leading or guiding portion 114 is provided which, in the neutral position shown in Fig. 1, extends completely through elongated bore 76 and part way into bore 72 therebetween. This leading portion terminates in an angularly extending cam face 115 which forms the bottom surface of laterally extending portion 109.

In the neutral or initial position illustrated in Fig. 1 cam face 115 is set to commence at the entrant edge of follower surface 77 though this relation is merely illustrative and may be varied by adding to or subtracting from shims 112a. In the final position, as shown in Fig. 5, the leading portion 114 has traveled considerably further into bore 72, while the cam surface 115 has traveled over the entrant edge of the cam-follower-surface 77 thereby drawing latch 73 against the action of springs 78. Hence locking latch 73 is fully retracted in which position it has been held since the Fig. 3 stage, due to the engagement of the vertical outer surface 109a of portion 109 with follower surface 77. The same having taken place on all the three latches, or cam-followers, the flanging punch 95 is now free to be forced downwardly when its upper end is engaged by leading ring 31 of the rolling anvil.

In order to prevent the flanging punch from moving out of position too soon, some means must be provided to resist the action of ring 31, but yet yield with it. As this means also acts to restore the flanging punch to its original position after the operation is completed, it must be indestructible and resilient. In the present instance this means takes the form of a heavy coil spring, though a rubber block would also be effective for a short time. In order to render the resilient means effective, three pins 116 (Figs. 1 to 5) are mounted to engage the underside of the laterally extending collar 96 and extend downwardly through recesses 83 and bores 84 into the aperture 53 of the bolster plate where they engage the upper surface of a compression collar 117. This compression collar is slidably mounted upon a tube 118 whose upper end is threadedly engaged at 119 in an aperture in the die shoe which is concentric about the axis of the die mechanism. The compression collar 117 has a laterally extending skirt 120 around its bottom, the underface of which is in engagement with the upper end of the compression spring 121. This spring is mounted on tube 118 and is held in place against the underface of skirt 120 by means of a retaining ring 122 which engages the lower end of spring 121 and is screw-threaded at 123 to the lower end of the tube 118.

Operation

When it is desired to secure a flange or bushing of the character described in an aperture in a sheet metal wall, the ram of the press being in neutral or retracted position as shown in Fig. 1, the bushing, which is already supplied with a gasket 9, is slipped over the top of the flanging punch and the container wall 1 is inserted between the die parts, being located by suitable stops which are normally provided projecting up from the bolster plate. The action is now started and as ram 10 descends, carrying with it the upper die part, the cutting edge 33 of the perforating punch engages the sheet slightly inside of the opening 98a in the flanging punch. Thus, continued downward movement of the ram severs a slug of desired size from the sheet, as shown in Fig. 2, and the same passes down through the aligned bores and out of the way. It is fitting to mention here that this stage of the action may be omitted in the event that a separate press, equipped with perforating dies has been used for blanking out the sheet metal wall. No such separate action is necessary, however, as the dies here described and blanking dies may be carried by a single press if it is powerful enough.

Once the sheet has been severed, it is engaged and clamped by clamping surfaces 44 and 100 and on continued downward movement of the ram, as shown in Fig. 2, the portion of the sheet between the perforation and the clamped portion is engaged by the drawing edge 47 of the embossing ring 38, which drawing edge acts with surface 44 to pull the sheet over the corner 98 of the flanging punch and strip it down over the outer surface of the flange or bushing 5, as shown in Fig. 3. During this drawing action, however, it is obvious that the sheet will embrace the reduce portion 8 of the neck 6 and tend to collapse the same. When this action does take place, however, the collapse is of limited extent, since the portion 8 will be arced inwardly at its top to engage the outer surface of the flanging punch at 97 (Fig. 2). This is the position in which portion 8 will be left after the sheet has been drawn down over it as shown in Fig. 3.

Were the flanging punch to remain in its original position, however, the collapse of portion 8 would render the picking up of the same by the curling anvil extremely difficult, for any anvil that would do it would have to have a sharp leading edge which would not stand up for any length of time under the rigours of this operation. Accordingly, as clamping surface 44 acts against surface 100 depressing the lower compression ring 99, cams 106 will travel downwardly causing the cam face 115 to engage the mouth of follower-surface 77 of the latches 73. Thus, by the time the sheet has been drawn to the position shown in Fig. 3, the latches 73 will have been drawn back out of the path of the collar 96 of the flanging punch, leaving the same supported by spring 121.

At approximately this position, the leading ring 31 of the rolling anvil will engage the top of the flanging punch and, as the action continues, push the same down to a sufficient extent that its top is withdrawn below the turned in end of portion 8. This allows the pickup portion 26, which is in advance of the true rolling surface and which has its inner end slightly inward of the corner 98 of the flange punch, to pick the portion 8 from the flanging punch and direct it onto the rolling sur-

face itself. On continued downward operation of the ram the flanging punch is pushed further out of the way, which is allowed by the compressibility of spring 121, and accordingly a complete roll or curl is formed out of portion 8 as shown in Figs. 5 and 8.

After the sheet metal wall has been perforated and while the neck is being formed in the same to overlie neck 6 of bushing 5, sufficient force can be provided without springs 19 being completely compressed. This compression of the springs follows no definite scheme, since the resistance of the outer wall of the bushing to the drawing of the sheet thereover is variable from one bushing to another. This variable even exists when bushings having the same corrosion resistant coating thereon are employed and, of course, a further variable factor is introduced when different coatings having different lubricating effects are employed as well as in situations where uncoated bushings or those dipped in a lubricating oil are being applied. Under the best conditions of lubrication, the spring may even give an added impetus by expanding a bit once the perforated sheet has its perforation drawn over the full diameter of neck 6, but as ideal lubrication is rarely encountered, this factor is of theoretical rather than practical importance. Powerful as the springs may be, they do not transmit sufficient force to enable the embossing 4, for reception of the flange 1, to be made. This takes place during that last fraction of the movement of the ram which corresponds to the thickness of flange 7 and at a time when springs 19 are completely compressed with the upper surface of ring 15 engaging the lower surface 14 of the shoe 11. Thus, the embossing is formed by the direct action of the press without any cushioning effect. It is at this stage also that the indicia, if any be desired, are impressed into the sheet metal wall.

The securing operation being completed, the ram of the press starts to return upwardly, pressure is released from the flanging punch and from the compression ring 99, whereupon the spring 121 acting through the pins 116 forces the flanging punch back to its original position; and in short order springs 11 are enabled, due to the retraction of cam surfaces 115, to return the latches 173 to locking position underneath collar 96. The mechanism is thus returned to its initial position ready to repeat its operation.

Modification

The modification shown in Figs. 14 and 15 distinguishes mainly from the form heretofore described in that an air cushion rather than a spring or rubber block is employed to allow the movement of the flanging punch to the extent required for forming an effective union between the flange or bushing neck and the container wall neck therearound. When a spring cushion is employed, its unreliability makes necessary the use of some means, such as the locking latches already described, for locking the flanging punch in position until a certain phase in the operation has been reached. On the other hand, employing an air cushion gives assurance that the flanging punch will not yield until the predetermined force for which the cushion has been set has been applied. However, adequate air cushions with the attendant auxiliaries, such as the source of the compressed air, the regulating valve, gauge and the like, are expensive and might not be as readily adaptable to presses already in use as would be the purely mechanical die mechanism heretofore

described. Thus, this type of mechanism is a true alternative of the one heretofore described and each has its particular advantages under certain conditions.

5 The sheet metal wall and flange or bushing to be secured thereto are, for the purposes of illustration, the same as those shown in Figs. 1 and 8. Hence the same reference characters will be employed thereon, but the elements of the die mechanism differ slightly in construction from those originally described and will accordingly be given different reference characters.

10 In the modification of Figs. 14 and 15, merely a fragment of the upper die shoe, or punch holder, is shown at 125 in Fig. 14. Mounted therebelow, for the same movement with respect thereto as is the compression ring of Fig. 1 with respect to its shoe, is a compression ring 126 which is held in aligned relation with 125 by guide bolts 127 whose heads 128 are slidably mounted in sockets formed in the die shoe 125. Resisting movement of the compression ring 126 towards the upper die shoe 125 are springs 129 of a size and location to suit the conditions imposed, as has been pointed out with respect to springs 19 of the Fig. 1 construction. Likewise, the lower face 130 of the die shoe and the upper face 131 of the compression ring are bored at 132 and 133 respectively to receive the ends of the springs 129.

15 30 The compression ring 126 is in the form of an annulus having as its inner face the cylindrical sliding surface 134 which terminates short of the bottom surface 135 of the ring due to the same being annularly recessed at 136. An embossing ring, generally shown at 137, underlies the ring 126 engaging the surfaces 135 and 136 of the same by portions 138 and 139 which co-mate therewith. This mated relation is secured and maintained by a series of bolts 140, only one of which is shown in order to avoid confusion. The embossing ring 137 has an interior cylindrical sliding surface 141 which is co-extensive with the surface 134 of the compression ring 126. The bottom of the embossing ring provides a pressure surface 142 designed to engage the sheet metal wall being worked upon, and an octagonal or other irregularly shaped depression 143 designed to cooperate with the flange 7 of bushing 5 in embossing the sheet metal wall to receive said flange.

20 45 55 60 65 70 The lower face 130 of the die shoe 125 is formed with a shallow circular depression 144 formed centrally thereof. This depression is of sufficient depth to receive and lock one end of an annular rolling anvil 145, which, in the present instance, is shown as double-ended. This anvil has a cylindrical external bearing or sliding surface 146 along which surfaces 134 of ring 126 and 141 of ring 137 slide. The rolling anvil is internally bored at 147. Each end of the anvil is provided with an annular channel 148 generally arcuate shaped in cross-section which commences slightly inward from the outer edge of the anvil and whose inner side merges into inclined pickup surface 149 whose nature and function is the same as the surface 26 of Fig. 1. Likewise pickup surface 149 terminates at its exterior in the leading ring 150 which is the same as the leading ring 31 previously described.

75 70 A perforating punch 151 having a perforating edge 152 and a securing shank 153 is mounted centrally of the upper die part and is retained in place by means of a securing bolt 154 extending through it and screw-threadedly received at 155 in the upper die shoe. The shank 153 of the

punch is received within the bore 147 of the rolling anvil, while the shoulder 156, in which that shank terminates, abuts against the lower face of the rolling anvil internally of the leading ring 150. In this manner, both the perforating punch and rolling anvil are positioned and secured in the exact location desired.

The lower die member has above its die shoe a guide or compression ring 160 retained in place by bolts 161 and urged upwardly by springs 162 in the same manner as is the ring 99 of Fig. 1. In order to assure accurate sliding of ring 160 when its upper face 163 is engaged by the sheet metal wall 1 as the same is urged downwardly through contact with surface 142, a bearing face 164 is provided thereon to slide along the outer face 166 of the lower anvil or seating ring 165 which serves to seat the flange or bushing 5. Above face 164 the bore of ring 160 has a portion 167 shaped to conform to and slide down alongside the edge of the laterally extending portion 7 of the flange or bushing 5. As ring 160 is precluded from rotating, portion 167 will thus preclude bushing 5 from rotating.

The anvil 165 has a seat 168 at its top on which the flange or bushing 5 is mounted and has a laterally extending securing portion 169 at its bottom which is rigidly secured in place in a corresponding recess 170 in the lower die shoe 171 by means of securing bolts 172.

A flanging punch 173, to flange a neck up from the container wall, having an opening in its top 174 to receive and cooperate with the perforating punch 151 and having a laterally extending supporting collar 175 at its bottom, is mounted within anvil 165 for vertical sliding movement with respect thereto. This sliding action is assured by the proper fit of bearing faces 176 and 177 on anvil 165 and flanging punch 173 respectively. The upper, outer corner 178 of the flanging punch is designed to facilitate commencement of the drawing action of the perforated sheet metal wall 1 over the flanging punch 173 and the flange or bushing 5. The portion 179 of the flanging punch just below the surface 178 acts as a support to prevent material inward collapse of the portion 8 of the flange or bushing 5 when the same is forced inwardly by the sheet metal wall 1 being drawn thereover. The flanging punch 173 is mounted on the flanging punch lift ring 180 whose ring portion 181 is slidably mounted within bore 182 of the die shoe 171. The upper end 183 of the ring 181 provides the mounting for the flanging punch whose portion 175 rests on end 183. At the bottom of ring 181 there is provided a laterally extending collar portion 184 which is slidably received in an enlarged bore 185 of the die shoe 171 and has an upper shoulder 186 engaging a similar shoulder 187 on the die shoe to prevent the ring 181 from moving upward beyond a certain position and consequently moving the flanging punch upward more than is desired.

It is also desirable to prevent ring 181 and the flanging punch 173 from falling out through the bottom of the lower die member when the same is lifted from the press, so provision is made for this in the form of locking bolt 188 (Fig. 15) whose flanged head 189 extends inwardly at the bottom of surface 185, thereby engaging collar 184 and preventing it from falling therebeyond.

As shown in Fig. 15, an air cushion, generally indicated at 190, is mounted below the die shoe or bolster plate of the press in conventional manner. The working parts of this cushion consist of a stationary piston 191 on which a movable

cylinder 192 is mounted for vertical movement by means of wall 193 and tongue 194. This movement is restricted by the extent of channel 195 at the lower portion of the piston wall due to the reception of tongue 194 in channel 195. Both the piston and cylinder are annular due to the necessity of having a continuous channel through which the slugs cut from the sheet metal wall may drop. Air under the pressure required to give the cylinder the desired resistance against displacement is introduced through the bottom of the piston and base of the housing as indicated at 196. This becomes effective against the cylinder due to openings 191a in the piston head. Otherwise, the construction of the cylinder and piston themselves, except as adapted to this particular use, is more or less conventional.

Mounted on the top 197 of the movable cylinder 192 is a die cushion lift ring 198 whose top 199 engages the underside of collar 184 of ring 181. The outer surface of ring 198 is recessed near its top as shown at 200 to allow for the flange 189 of stop screw 188. Ring 198 is slidably mounted in the passage 201 formed through the bolster plate of the press. The bottom 202 of the ring is of sufficient extent at its engagement with the top 197 of the cylinder 192 to distribute the downward force applied over a sufficient area of said cylinder to prevent its becoming damaged in spite of continuous use.

The operation of the modification shown in Figs. 14 and 15 is more simple than that of the form previously described. Once the sheet 1 has been punched by perforating punch 151, the upper die member continues to travel downwardly, whence surface 142 engages sheet 1 and forces it down against surface 163 causing the perforated portion of the sheet to be drawn over the corner 178 of flanging punch 173, thereby flanging the sheet surrounding its perforation. This flange engages the reduced upper end 8 of bushing 5 partially collapsing the same against the surface 179 of the flanging punch the same as is done in the form previously described. On further downward travel of the upper die member the embossing ring 137 and the guiding ring 160 are retracted against their spring actions so that leading ring 150 comes into engagement with the top of the flanging punch 173. The force of this engagement steadily increases with continued downward movement of the ram of the press, since the ram carries the upper die member.

The resistance offered by the air cushion 190 is determined by the pressure of the air therein. Once that resistance has been overcome the movable cylinder 192 will ride down over the stationary piston 191. The force tending to cause, and finally causing, the air cushion to give is that which is impressed by the leading ring 150 on the flanging punch 173. The latter transmits it to the flanging punch lift ring 180, which, in turn, transmits it to the die cushion lift ring 198. As these rings and the flanging punch are arranged to slide, they will do so until the upper die member has reached the end of its travel. This action is merely of sufficient extent to remove the support of the flanging punch from the upper reduced portion 8 of the bushing 5 and thus to enable the pickup portion 149 to direct that portion of the bushing into the rolling surface 148 of the anvil 145. Thus, the reduced end 8 of the bushing is rolled over the end of the container wall flange or neck to make the product shown in Fig. 8.

Once the joining of the bushing with the sheet metal wall has been completed, the ram of the press will retreat and ring 180 will be free to act as a knockout portion raising the container wall, thereby facilitating its removal. Since the air pressure on the air cushion 190 is maintained constant, cylinder 192 will move upward carrying with it ring 198 which in turn carries ring 180 so that the latter may restore the flanging punch 173 to its original position ready for repetition of the operation. As was previously pointed out a stop surface 187 was provided on the die shoe 171, which surface is engaged by a corresponding stop surface 186 on the lift ring 180. These surfaces act as a control on the upward movement of the lift rings and flanging punch, thereby assuring that the flanging punch will be restored to the exact position desired for the succeeding operation.

While only two forms of structure have been shown embodying the invention, it is understood that other changes in details and arrangement of parts may be made without departing from the spirit and scope of the invention as defined in the claims.

Having described our invention, what we claim is:

1. In single operation die mechanism for applying flanged bushings to perforated metallic sheets, means to draw the sheet to a neck surrounding the bushing with part of the bushing neck extending through the perforation, means to roll the extending part of the bushing neck over the end of the surrounding neck of the sheet and means movable during part of the drawing operation to guide the extending part of the bushing neck into proper engagement with the rolling means, said guiding means being movable at substantially the end of the drawing operation to leave the extending part of the bushing neck free for engagement by the rolling means whereby bushings may be seated in place in metallic sheets with uniformity.

2. In die mechanism of the character described, a stationary lower die member and a movable upper die member, an anvil for supporting a flanged bushing on said lower die member, a flanging punch slidably mounted within said anvil and normally arranged to extend above the top of a bushing supported thereon, a ring on said upper die member cooperating with said flanging punch to flange a perforated sheet engaged there-between, a resilient member mounted below said flanging punch and means operably supporting said flanging punch on said resilient member whereby a sliding movement of said flanging punch in response to the movement of said upper die member may be effected only against the action of said resilient member.

3. In die mechanism of the character described, a stationary lower die member and a movable upper die member, an anvil for supporting a flanged bushing on said lower die member, a flanging punch slidably mounted within said anvil and arranged to normally extend above the top of a bushing supported thereon, a compressed air cushion mounted below said flanging punch, said cushion having a stationary portion and a portion movable with respect thereto against the air pressure acting therebetween, collar means for operably mounting said flanging punch on the movable portion of said air cushion and means on said upper die member operable at a predetermined point in the movement of said upper die member for engaging said flang-

ing punch to move the same against the resistance offered by said air cushion.

4. In die mechanism of the character described, a movable upper die member, a stationary lower die member, a seating anvil on the lower die member for supporting a flanged bushing thereon, a flanging punch extending above said seating anvil and mounted for slidable movement with respect thereto, a rolling anvil carried by the upper die member and a leading ring on the upper die member operable in advance of the rolling portion of the rolling anvil to engage the flanging punch and move the same out of the path of operation of the rolling anvil.

5. In die mechanism of the character described, a movable upper die member, a stationary lower die member, a seating anvil on the lower die member for supporting a flanged bushing thereon, a flanging punch extending above said seating anvil and mounted for slidable movement with respect thereto, a rolling anvil carried by the upper die member, a leading ring on said rolling anvil operable in advance of the rolling surface thereof to engage the flanging punch and impart slidable movement thereto and a guiding surface interposed between said leading ring and the rolling anvil to guide the end of a bushing neck from the surface of said flanging punch onto the actuating surface of said rolling anvil.

6. The process of mounting an annular device in a perforated sheet metal wall which comprises, supporting the device at one side of the wall, introducing the device into the perforation while limiting the extent to which the device may collapse until a portion of the device extends through the perforation, removing the limiting means from the extending portion of the device at a predetermined stage of the introducing action and forming the extending portion of the device against the sheet metal wall to retain the device in place therein.

7. The process of mounting a flanged bushing having a reduced end in a perforation in a sheet metal wall which comprises, supporting the reduced end against collapsing inwardly, by resiliently mounted means, drawing the perforated wall over the bushing to form an embossing encompassing said flanged end and a neck overlying the body of the bushing with the reduced end of the bushing extending above said neck, overcoming the resilience of the mounting to remove the supporting means from the reduced end and rolling said end of the bushing over the adjacent end of the neck to secure the bushing in place in the wall.

8. In single operation die mechanism for applying flanged bushings to perforated metallic sheets, means to draw the perforated sheet over the bushing, with the bushing neck received in the perforation, means to form the bushing over the adjacent portion of the sheet to retain the same in place therein, and pressure supported means to retain the bushing in line with the forming means until the bushing is engaged with the forming means, said retaining means being engaged by said forming means, and the forming means exerting a pressure on said retaining means to move the same against the supporting pressure.

9. In single operation die mechanism for applying bushings to perforated sheets, means to form a sheet into a neck over the bushing with part of the bushing extending through the perforation, means to substantially prevent col-

lapse of said part of the bushing as the sheet is formed thereover and means for removing the preventing means from effective position at a pre-determined stage in the applying operation.

10. In single operation die mechanism for applying bushings to perforated sheets, means to shape the material of the sheet to receive the bushing with part of the bushing extending through the perforation, means to substantially prevent collapse of said part of the bushing as the sheet is shaped thereover, and means for withdrawing the preventing means to render the preventing means ineffective at a predetermined stage in the applying operation.

11. In single operation die mechanism for applying bushings to perforated sheets, means to shape the material of the sheet to receive the bushing with part of the bushing received in the perforation, said means including a device to substantially prevent collapse of said part of the bushing when the sheet is shaped thereover and means for moving said device out of collapse-preventing position with respect to said part of the bushing as the bushing is seated in the sheet.

12. In single operation die mechanism for applying bushings to sheets of material, means to perforate the sheet; means acting during the single stroke of the mechanism to introduce part of the bushing neck into the perforation, means forming part of said perforating means to substantially prevent collapse of said part of the bushing as it is introduced into the perforation and means for removing said preventing means from effective position at a predetermined stage in the introducing operation.

13. In single operation die mechanism for applying bushings to sheets of material, means to

perforate the sheet, means to shape the sheet over the bushing with part of the bushing received in the perforation, means forming part of said perforating means and part of said shaping means to substantially prevent collapse of said part of the bushing as the sheet is shaped thereover and means for withdrawing said preventing means from effective position at a pre-determined stage in the operation.

14. In single operation die mechanism for applying bushings to perforated sheets, means to seat the bushing in place in the perforation with a portion of the same extending through the perforation, means to limit the extent to which the said portion of the bushing may be collapsed by the action of the surrounding sheet during the seating operation, forming means for forming the extending portion of said bushing over the adjacent sheet and means carried by said forming means for moving said limiting means out of limiting position at a predetermined stage in the operation to enable said forming means to operate.

15. In single operation die mechanism for applying bushings to perforated sheets, an apertured anvil for supporting a bushing, a flanging punch slideably received within said anvil and the bushing supported thereon and normally arranged to extend slightly above said bushing, pressure responsive means carried by said die mechanism and means interconnecting said flanging punch with said pressure responsive means for controlling the sliding movement of said flanging punch.

CERTIFICATE OF CORRECTION.

Patent No. 2,325,929.

August 3, 1943.

EARL M. AMESBURY, ET AL.

It is hereby certified that error appears in the printed specification of the above numbered patent requiring correction as follows: Page 5, first column, line 23, for "therebetween" read --therebeneath--; and that the said Letters Patent should be read with this correction therein that the same may conform to the record of the case in the Patent Office.

Signed and sealed this 29th day of February, A. D. 1944.

Leslie Frazer

(Seal)

Acting Commissioner of Patents.
